UNITED STATES PATENT OFFICE.

WILLIAM ROW, OF WHEELING, WEST VIRGINIA, ASSIGNOR OF ONE-HALF
TO ALEXANDER HIRTH, OF SAME PLACE.

BOILER-CLEANER.

SPECIFICATION forming part of Letters Patent No. 349,955, dated September 28, 1886.

Application filed June 23, 1886. Serial No. 206,019. (No model.)

To all whom it may concern:

Be it known that I, WILLIAM Row, a resident of Wheeling, in the county of Ohio and State of West Virginia, have invented certain new and useful Improvements in Boiler-Cleaners; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to horizontal steam-boilers in general, and its object is to provide means of removing the scale and sediment which accumulate in the same in a simple and expeditious manner.

To this end the invention consists of a "blow-off" pipe of peculiar shape, as hereinafter fully described, which is secured lengthwise to the interior of the boiler and connected with an exterior pipe provided with a valve to regulate the steam-pressure at the will of the operator.

In the drawings, Figure 1 is a vertical lengthwise section; Fig. 2, a vertical cross-section of a boiler, showing my invention applied to the same.

Like letters of reference refer to like parts.

The letter A designates an ordinary form of boiler, inclosed by brick walls or casing H, in the usual manner.

E is the furnace; G, breeching.

B are fire-flues extending entirely through the boiler.

C is a pipe passing through the back end of the boiler and extending forward to a point just over the third fire-sheet of the boiler, where it terminates with a trumpet-shaped mouth turned downward to the bottom of the boiler and within a close distance of the same, preferably three-fourths of an inch from the bottom. This pipe C is suspended in the boiler by means of hangers b b, resting upon the flues of the boiler, placed at suitable distances apart, and it is provided with a number of small holes, a a, on each side of the pipe, for the purpose of relieving it from the pressure

of the steam during the operation of blowing off.

F is a valve on the exterior end of the pipe to regulate the pressure and operate the device.

d is an extension of the pipe C, which can be made any suitable length to carry the waste steam away.

When it is thought desirable to clean out the boiler, the valve F is opened and the steam and water caused to exhaust through the blow-off pipe C. The enforced flow of the water outward through the blow-off pipe in its passage from the rear end of the boiler to the front end of the same, where the mouth of the blow-off pipe is located, operates to loosen and carry with it the accumulation of sediment and scale deposited along the bottom of the boiler. The small openings a a in the side of the pipe are proportioned in area to relieve the great pressure of the steam and water concentrated, as it were, upon one end of the pipe, and at the same time serve to remove the sediment, which may be checked in its passage to the forward end of the boiler.

The advantage derived from the funnel-shaped open-end pipe projecting into the boiler with its mouth turned downward toward the bottom of the boiler is that a suction is created from the bottom of the boiler toward the mouth of the pipe, carrying with the flow of water and steam all the sediment and scale which usually collect at this portion of the boiler.

In some cases, where mud-drums are attached to the boilers, the escape-pipe could be run through the drum and a valve placed on the outer end; but practical experience has taught me that where my device is used a mud-drum is not necessary to effect a thorough removal of all scale and sediment.

Having described my invention, what I claim, and desire to secure by Letters Patent of the United States, is—

1. The combination, with a steam-boiler, of a blow-off pipe provided with a series of perforations along its side, and having a trumpet-shaped open end or mouth, said pipe suspended within the boiler with the mouth turned

downward and in close proximity to the bottom of the boiler, and means to regulate the pressure of the steam, substantially as and for the purpose set forth.

5. 2. The combination, with the boiler A, of the pipe C, having a trumpet-shaped open end, D, and perforations *a a*, hangers *b b b*, valve F, and escape-pipe *d*, substantially as and for the purpose set forth.

In testimony that I do claim the foregoing as to my own I hereby affix my signature in presence of two witnesses.

WILLIAM ROW.
